Primary Examiner — W. A. Teddy Falloway*Assistant Examiner* — Sarah J Ault(74) Attorney, Agent, or Firm — OSTROLENK FABER LLP(57) CLAIM

The ornamental design for religious motif jewelry, as shown and described.

DESCRIPTION

FIG. 1 is a perspective view of religious motif jewelry showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The black areas on the design represent a contrasting appearance.

The broken lines in the drawings illustrate portions of the religious motif jewelry that form no part of the claimed design.

1 Claim, 6 Drawing Sheets(56)
